UNITED STATES PATENT OFFICE.

GEORGE B. DURKEE, OF CHICAGO, ILLINOIS, ASSIGNOR TO LYON & HEALY,
OF SAME PLACE.

TAIL-PIECE FOR MUSICAL INSTRUMENTS.

SPECIFICATION forming part of Letters Patent No. 447,946, dated March 10, 1891.

Application filed February 8, 1889. Serial No. 299,200. (No model.)

To all whom it may concern:

Be it known that I, GEORGE B. DURKEE, a citizen of the United States, residing at Chicago, in the county of Cook and State of Illinois, have invented a certain new and useful Improvement in Tail-Pieces for Stringed Musical Instruments, of which the following is a specification.

The object of my invention is to provide an exceedingly simple and economical construction of tail-piece for stringed musical instruments, such as banjos and mandolins, and to attain certain other desirable ends in devices for such purposes, as hereinafter more particularly set forth.

I construct my improved tail-piece of stout sheet metal, which is stamped or struck up so as to provide it with a set of string-holding fingers which rise from the plane of the plate, whereby certain advantages hereinafter set forth are attained.

In applying said tail-piece to a mandolin its body portion is bent along one edge to provide a suitable rest for certain portions of the strings, as indicated in the accompanying drawings, in which—

Figure 1 represents a central longitudinal section taken through a mandolin with my improved tail-piece applied thereto, a portion of the neck of the mandolin being broken away for convenience of illustration. Fig. 2 represents in perspective my improved tail-piece and shows a couple of strings having looped ends caught on to a couple of the string-holding fingers. Fig. 3 represents a blank from which my improved tail-piece may be made, the configuration of the tail-piece being partially indicated in dotted lines, as are also the slits that are to be cut in the blank during and as a part of the operation of striking up the string-holding fingers.

In said drawings, A indicates as a whole my improved tail-piece, which in Fig. 1 is applied to the flattened back or tail end portion b of a mandolin B. The body portion a of the tail-piece consists of a flat or substantially flat metal plate, which may be cut as a blank from any suitable strip or sheet of metal. The string-holding fingers a' are formed by striking them up from the plate, whereby they shall rise at an angle to the plane of the

plate, and hence permit the loops at the ends of the strings to be readily caught onto them. In striking up these string-holding fingers no metal is wasted, and the strength of the body portion is not materially lessened, since each string-holding finger is formed simply by a die or tool adapted to cut in said plate three slits a², a³, and a⁴, substantially in the line of a parallelogram and running into one another, as in Fig. 3, wherein said slits are indicated by dotted lines in a blank that is to be stamped up, it being observed that the cutting of the slits and the striking up of the fingers can be performed at one operation. When applied to a mandolin, as in Fig. 1, the edge portion a⁵ is bent substantially at right angles to the remaining portion of the plate or body, whereby while the main portion of said plate or body may rest against the flattened end b of the mandolin the flange or lip a⁵ may rest upon the face b of the mandolin, and thereby provide a metallic rest for the strings, and also prevent them from being cut by sharp corners, it being observed that the flange or lip a⁵ should be bent so as to provide between said flange and body of the plate a long rounded corner a⁶.

An exceedingly important feature involving thus striking up the string-holding fingers so that they shall rise at an angle to the plane of the plate is the admissibility of the flat plate or body a being placed and secured directly against the flat portion of the body of the instrument, it being observed that by such arrangement the loops c of the strings C can be readily caught on to the string-holding fingers, which could not be done if said fingers were in the plane of the plate a and partially surrounded by an enlarged opening, since in such case the string-holding fingers would lie against the body of the instrument and therefore render it impossible to attach the strings of the fingers without raising the tail-piece as a whole from the body of the instrument by placing between the two some intervening support, which arrangement is not desirable. It will also be observed that I provide the body a of the tail-piece with screw-holes a⁷, whereby the said plate a can be laid directly against the flattened body of the instrument and secured

thereto by ordinary screws, which serve to hold the plate rigid with the body of the instrument and in effect as integral therewith.

D indicates a cover or guard, which consists of a plate provided with the marginal lips or flanges d and d'. Said guard is hinged to the tail-piece, and can be either brought into position to cover the tail-piece, as in Fig. 1, or thrown back, as in Fig. 2, to permit the strings to be caught onto the fingers a'.

In severing the blank or plate a from a strip or sheet of metal said blank can be cut with a tongue at one end, as indicated in dotted lines at a³, Fig. 3, and said tongue can be bent to provide a pintle-bearing, as in Figs. 1 and 2, wherein the pintle-bearing thus formed is also indicated, as a³.

The guard D can be provided with pintle-bearings d² for the pintle d³, which extends through the bearing a³, although as a matter of course the plate a could be provided with two pintle-bearings and the guard could be provided with one pintle-bearing should such arrangement be desired.

I do not herein broadly claim a guard for covering the point whereat the strings are held, since such is made the subject-matter of a claim in my application No. 301,265, filed

in the United States Patent Office on or about February 26, 1889.

30

What I claim as my invention is—

1. A tail-piece for the purpose set forth, consisting of the metal plate a, provided with a set of struck-up string-holding fingers a', which rise from the plane of said plate, substantially as described.

2. The tail-piece A, consisting of a metal plate a, provided with a flange a', and having the struck-up fingers a', which rise from the plane of the plate, substantially as and for the purpose described.

3. The combination, with a mandolin, of the tail-piece A, provided with the body-plate a, having struck-up fingers a', said plate a being fitted directly against the flattened end b of the mandolin-body, substantially as and for the purpose described.

4. The combination, with the metal plate provided with means for holding the strings and having a pintle-bearing, of the guard pivoted to said pintle-bearing and adapted to cover said plate, substantially as described.

GEORGE B. DURKEE.
